UNITED STATES PATENT OFFICE.

ORON K. SKIDMORE, OF PENNS GROVE, NEW JERSEY.

CONCRETE-STEEL TIE.

1,283,930.

Specification of Letters Patent.

Patented Nov. 5, 1918.

Application filed March 16, 1918. Serial No. 222,906.

To all whom it may concern:

Be it known that I, ORON K. SKIDMORE, a citizen of the United States of America, residing at Penns Grove, in the county of 5 Salem and State of New Jersey, have invented new and useful Improvements in Concrete-Steel Ties, of which the following is a specification.

The invention relates to improvements in 10 railroad ties made from concrete and partially surrounded by steel.

Its principal object is to provide a tie of 15 this character in which two channel members are employed and held in spaced relation by suitable connecting means, the space between the two channel members being filled with cement or concrete.

A further object of the invention is to 20 provide a rail engaging means for such a tie, whereby the rail may be securely held in place thereon, the rail engaging means comprising members adapted to engage the base flanges of the rail and to pass through the web of one of the channel members and to 25 engage locking devices therebeneath, the locking devices being appropriately embedded in the concrete.

A still further object provides for making 30 the locking devices removable.

A still further object is to provide a tie of 35 this character which is simple and cheap in construction but yet durable and effective in operation.

Still further and other objects will appear 40 as the invention is set forth in detail in the description which follows.

To the exact embodiment in which it is shown and described, the invention is not to 45 be restricted. Actual practical application 50 may make manifest certain desirable changes or alterations and the right is claimed to make any which do not deviate from the scope of the subjoined claims.

In the accompanying drawings:

Fig. 1 is a longitudinal sectional view 45 of the improved tie and portions of rail sections mounted thereon.

Fig. 2 is a section on a line 2—2 of Fig. 1.

Fig. 3 is a top plan view of a portion of 50 the improved tie.

Fig. 4 is a perspective view of one of the washers used in conjunction with the rail attaching bolts.

In the drawings, the improved tie is 55 shown as comprising channel portions 1 and 2 which are held in spaced relation to each

other by appropriate tubular spacing members 3. The spacing members obtain centrally with respect to the width of the channel members and one of said spacing members is medially disposed with reference to the length of the channel members, while the other spacing members are positioned at appropriate distances from the ends of the channel members. Bolts 4 pass through the 60 two channel members and through the spaces and serve to hold all of these parts rigidly 65 connected together.

The space between the two channel members is appropriately filled with concrete or 70 cement, thereby forming a solid tie with a cross sectional area whose one dimension is the width of the channel members and whose other dimension is the distance between the upper and lower faces of the two channel 75 members. The channel members are, of course, so connected together that their flanges are directed toward each other.

In the web of the channel member 1 there are provided holes 6 which are elongated in 80 the direction of the length of the channel member. These holes are provided for the purpose of permitting the rail attaching bolts 7 to pass through them. The holes 6 are arranged in pairs, one pair on either side 85 of the longitudinal center of the channel member and at such a distance therefrom that the two rails 8 may be appropriately attached to the tie, so that the specified regulation distance may obtain between the edges 90 of the treads of the two rails. One of the holes 6 of each pair is positioned closer to the longitudinal center of the channel member than the other of that pair and the two holes of each pair are diagonally disposed 95 with reference to each other, the one being near one flange of the channel member and the other near the other flange of the channel member. The holes are elongated to facilitate the removal of the rails without 100 the complete detaching of the rail bolts from their attendant locking devices.

The tie is formed with tapering blocks 9 set in the concrete so that their thinner ends lie below the holes 6 and their thicker ends 105 lie flush with the flanges of the channel member, which together with the concrete or cement form the sides of the tie. The blocks 9 are inclined with reference to the web of the channel member 1 and the concrete 5 is 110 cast or molded around it. Each block 9 is provided with a hole registering with the

hole 6 just above the block and this hole is broached from the under face of the block leaving a pocket 10 which is adapted to loosely receive the nut 11, the shape of the pocket conforming to the shape of the nut which it receives.

The rails 8 are attached to the tie after their base flanges have been positioned on top of the channel member 1, the bolts 7 effecting this attachment in conjunction with washers 12. These washers 12 are circular in plan and are provided with concentric body holes for the bolts 7. The top and bottom faces of the washers are parallel for the most part, but these washers are adapted to lie upon the base flanges of the rail and, therefore, that portion of the under face which engages the tie is beveled off to the angle conforming to the angle which the top face of the flange forms with the bottom face thereof.

The bolts 7 are adapted to be threaded into the nuts 11 carried in the pockets 10 of the blocks 9 and when these bolts are firmly screwed down, after the washers 12 have been attached to them, the rails 8 are firmly held in place, since the nuts 11 will be drawn up against the tops of the pockets and the washers 12 drawn down on top of the rail flanges.

In the event that any bolt 7 should become sheared off, so that it could not be readily detached from its attendant nut 11, the block 9 connected with the damaged bolt 35 may be easily removable from the tie and such damaged bolt and its attendant nut conveniently removed. The operation for removing the block 9 consists only in placing a punch or broach through the hole 6 and having it impinge upon a portion of the block. The operation of driving upon the punch then serves to release the block from the tie, the tapering shape and diagonal position of the former rendering its removal 40 easy after it has been once loosened.

As before stated the elongated holes 6 permit the removal of the rails, when it is

so desired, by the loosening of the bolts 7 without the complete detaching from the nuts 11, as the bolts 7 having once been loosened may be shifted to bring their heads and the beveled portions of the washer 12 out of the way of the rails 10.

The foregoing description taken in conjunction with the drawings makes all of the features of the invention apparent and further description is therefore unnecessary.

The invention having been described what is claimed as new and useful is:

1. In a railroad tie, the combination with 60 a solid tie having holes formed in the upper face thereof, of members embedded in the tie and removable therefrom, whereby rail securing devices may be inserted through the holes and engaging with said members. 65

2. The combination of a solid tie having holes formed in the upper face thereof, with tapering shaped blocks embedded in the tie and diagonally disposed and provided with holes registering with the holes in the tie, 70 the said holes in the blocks being broached from the bottom face thereof to conform to the shape of a nut, whereby rails may be attached to the tie by means of the use of bolts and their attendant nuts.

3. The combination of a concrete steel tie formed of two channel members in spaced relation and containing concrete between them and having means for attaching the channel members together, with tapering 80 blocks set in the concrete so that the thinner ends of the blocks lie against the web of one of the channel members and the thicker edges of the blocks lie flush with the flanges thereof, the said channel members and the 85 blocks being provided with elongated holes, the holes in the blocks being broached from the underface of the blocks to conform to the shape of a nut, whereby rails may be attached to the tie by means of appropriate 90 bolts and their attendant nuts.

In testimony whereof I affix my signature.

ORON K. SKIDMORE.
